Term of patent 14 years

Int. Cl. D1—01

U.S. Cl. D1—24

Fig. 1

Fig. 2

Fig. 3

Fig. 4

FIGURE 1 is a side elevation of a bun or the like showing my new design, the side opposite thereto being similarly plain and unornamented:

The broken line showing in FIG. 1 of a conventional frankfurter is merely for illustrative purposes.

I claim:

The ornamental design for a bun or the like, as shown and described.
